CIRCUIT BREAKER

William M. Scott, Jr., Bryn Mawr, Pa., assignor
to I-T-E Circuit Breaker Company, Philadelphia, Pa., a corporation of Pennsylvania

Application April 27, 1940, Serial No. 332,037

5 Claims. (Cl. 200—168)

This invention relates to switch gear and circuit breakers, and more particularly to a panel type combination switch and circuit breaker adapted for use in branch circuits of various types and arranged to be mounted upon a panel board together with other similar devices for controlling a plurality of circuits.

This invention is particularly directed to the housing of the panel board circuit breaker and the arrangement of the housing to facilitate assembly and to provide integral support for the members of the circuit breaker.

In the operation of branch circuits, it is frequently important to connect or disconnect individual circuits from the main line without interfering with the operation of other similar circuits, and to arrange for overload protection for individual circuits so that in the event of any fault in any particular branch, that particular circuit may automatically be disconnected without interfering in any way with the operation of other circuits or with the operation of the main circuit itself.

Thus, in the operation of a plurality of small motors for various purposes in a shop, it is important that any fault occurring in the circuit to a particular motor should not affect the operation of other motors or the main line to the end that continuous operation should, as far as possible, be maintained.

Likewise, in the operation of multiple dwellings or apartment houses where a plurality of individual circuits for different apartments are all connected to a single main line, it is important that any particular circuit to any particular apartment be readily connectible to and disconnectible from the main line and that any fault in any particular circuit should not disturb the operation of any of the other circuits.

Accordingly, the purpose and object of the present invention is to provide a simple combination on-off switch and circuit breaker which may be mounted upon a panel board and connected between the main bus and the individual branch circuits in order to provide suitable manual or automatic control for each of the individual circuits.

In order to provide for panel board mounting of this type and in order further to provide for simplicity in operation and assembly and to facilitate mounting upon the panel board, it is important that the particular combination switch and circuit breaker be compact and nevertheless so arranged as to obviate any internal faults or short circuits.

Accordingly, instead of providing for the creation of a simple air-gap between the movable contact member and the stationary contact in the present "on-off" switch circuit breaker combination, it is important to provide for the interposition of actual physical dielectric barriers between the two contacts when they separate. For this purpose, the movable contact is biased toward contact closing position and is separated from the stationary contact by the movement of a barrier between them, one barrier being used for manual operation, another for automatic operation; the two barriers moving in the same plane and the manually interposable barrier being used to reset the automatically interposable barrier in non-interposing position when that is desired.

The circuits and apparatus may be designed to carry (a) a maximum current above and below which small variation may occur, (b) a heavy momentary inrush current as in thermal devices such as lamps where operating resistance increases after being switched on, (c) starting currents for motors, (d) short periods such as may occur in motors.

When these momentary increases occur, the length of time they last should be limited by the circuit breaker, preferably in accordance with the square of the current and directly in accordance with the time (I^2T). Whenever the current exceeds the normal maximum value, then however, the circuit should be interrupted as quickly as possible.

The present circuit breaker will trip automatically under either of these conditions in response to either an instantaneous trip mechanism which will operate where resistance drops to substantially zero, or to a thermal trip mechanism operating in accordance with the aforementioned I^2T characteristic.

An important object of the present invention is to so arrange the housing of the circuit breaker that all of the members thereof may be supported by integral formations of the housing and members integrated therewith.

Still another and extremely important object of the present invention is the arrangement of the housing of the combination switch and circuit breaker, and the various parts thereof in such manner as readily to facilitate assembly. That is, the housing is so formed and each of the parts is so formed that the parts may readily successively be placed in the housing from one side, the assembly operation requiring merely a series of successive steps without any requirement

for complicated tools or complicated supporting and holding means for combining and supporting the members during assembly.

A still further object of the present invention is to so arrange the housing and each of the parts that when the cover plate is secured to the housing at one side thereof, each of the parts is securely locked in operative position.

Many other objects and uses of the present invention will in part be apparent and in part 10 pointed out in the following description and drawing, in which:

Figure 1 is a side view of the combination switch and circuit breaker with the cover plate removed and with the contacts and various members arranged in open circuit position.

Figure 2 is a cross-sectional view taken on line 2-2 of Figure 1.

Figure 3 is a view corresponding to a portion of Figure 2, showing the contacts in closed circuit position.

Referring now to Figure 1, there is here shown a combination switch and circuit breaker which comprises a principal housing 20 arranged to carry, support and position each of the members of the "on-off" switch and circuit breaker. The housing 20 has peripheral ledges 21, 21 upon which a suitable cover plate 21a may be mounted and secured thereto by means of the rivets 22, 22.

The combination switch and circuit breaker comprises a manual operating handle 23 and circuit connecting means, separable contacts and automatic tripping means hereinafter more particularly described.

The combination switch and circuit breaker of Figure 1 is of a form and construction peculiarly adapting it for panel board operation for controlling a series of branch or subsidiary circuits fed from a main line or bus.

Figures 1 and 2 show the various parts of the 40 switch and circuit breaker combination in the ordinary open circuit position produced when the manual operating handle 23 has been moved to open circuit position and the contacts have been separated without the intervention of any automatic elements.

As will readily be seen from Figures 1 and 2 the combination switch and circuit breaker comprises a terminal or circuit connecting member 30 having any suitable means such as the threaded perforation 31 therein for connecting the circuit breaker to one terminal of the circuit. The current is led to the connecting lug 30 (which is preferably connected to the load) from the integrally associated conductive bar 32 which is connected, through the projecting lug 33 of the bar 32, to the bi-metallic element 34.

The bi-metallic thermal element is at the bottom thereof connected to the flexible wire connection, preferably a copper braid 35 which is 60 in turn conductively connected to the solenoid coil 37. The solenoid coil 37 is connected by means of the integral connecting bar 38 to the movable contact-carrying bar 39, the said contact-carrying bar being preferably an integral 65 extension of the bar 38.

Contact carrying bar 39 as will preferably be seen in Figure 2, carries the main movable contact block 40. The current enters the movable contact block 40 at the movable contact surface 41 (see Figure 3) when the combination switch-circuit breaker is closed from the stationary contact surface 42.

The stationary contact surface 42 is carried 75 by the stationary contact supporting bar 43 (see

Figures 2 and 3) which is in turn connected by the angular lead-in bar 44 (see Figure 1) to the opposite terminal or lead 45 into which the current may be led from the bus bar.

It will thus be seen that when the circuit breaker is so arranged that one terminal 30 thereof is connected through the load to one pole of the circuit and the opposite terminal 45 (connected to the stationary contact) is connected to the opposite pole of the circuit, then the current path is through the two contact surfaces 41 and 42, and that any breaking of these contacts, that is, any separation thereof, will result in an opening of the circuit. Such separation of the contacts may be accomplished either manually, whenever it may be desired, or automatically in response to faults or over current conditions occurring in the circuit which the present circuit breaker is designed to protect.

For the purpose of separating contact surfaces 41, and 42, it may be sufficient merely to move the movable contact a sufficient distance away from a stationary contact so that the air or gases between them furnishes sufficient dielectric interposition to prevent effectively the passage of current therebetween.

Where, owing to the fact that for panel board mounting of these circuit breakers, the various dimensions thereof must be compressed as far as possible and the amount of travel permissible in the movable contacts is relatively limited, then in order to effectively break the contacts apart so that no current may flow therebetween, the present structure relies not on a sufficient movement of the movable contact to accomplish this purpose, but principally on the interposition of a physical barrier of dielectric material which either effectively serves to lengthen any possible arcing path beyond the limits within which an arc may be maintained for the particular current and voltage rating of the circuit breaker or effectively serves to prevent any arcing path whatever.

Accordingly, the manually operated interposer 45 50 mounted on the manual operating lever 23 by means of the rivets 51, 51 secured to the foot 52 may be utilized to separate the contacts and open the switch. The entire manual operating lever comprises a finger grasping portion 60 which may be knurled to ensure a firm fit, a central pivoting portion 61 which carries the foot 52 and to which is connected the interposer 50. The interposer 50 is preferably formed and pressed from suitable insulating dielectric material to a thickness facilitating interposition between the movable and stationary contact. The central portion 61 has a central opening 70 into which projects a knife edge 71 preferably integrally molded with the entire handle portion 23.

When the manual operating handle 23 is mounted upon the spindle 72 so that the knife edge 71 thereof registers with the angle 74 of the spindle and so that the perforation 70 of the central portion 61 of the manual operating member cooperates with the remainder of the spindle 72, then the manual operating handle 23 may readily be rotated about the spindle within definite limits or stops. That is, the manual operating handle may be rotated from the open circuit position shown in Figure 1 to a closed circuit position wherein the movable contact 40 may be pressed against the stationary contact 42 as seen in Figure 3, in each case the side of the knife edge approaching one of the surfaces of the cut-out 73 of the spindle.

During the actual rotation, the principal bearing surface between the manual operating handle and the spindle is the knife edge 11 of the manual operating handle pressing into the angle 14 of the spindle. Thus even though the perforation 70 of the manual operating handle is slightly larger in diameter than the greatest diameter of the spindle, nevertheless the pressure of the knife edge 11 of the handle into the angle 14 of the spindle furnishes an efficient, playless bearing.

The spindle 12 by being preferably integrally molded with the side wall of the housing or by being integrated therewith in any suitable manner providing a positive positioning element for the rotating members and provides a simplified means upon which the rotating members may be assembled.

The finger grasping portion 60 of the manual operating lever 23 projects through the slot 80 in the upper surface of the housing where its movement from open circuit to closed circuit position is limited by the integrally formed shoulders 82 and 83.

The spring 90 is so arranged relative to the center of rotation of the manual operating lever that it yieldingly biases the member 23 either in open or closed circuit position by reason of the fact that the spring passes upon the center for either position of the member 23 and thus yieldingly locks the manual operating lever in place.

The compression spring 90 is mounted on a slideable steel bar or link 91 which terminates at one end thereof in a bearing surface 92. The end 93 of the bar projects through an opening in a suitable bearing plate 95 and slides freely in said opening; the opposite end of the bar is engaged in a notch 96 of the central portion 61 of the manual operating arm 23.

The spring 90 is thus maintained under compression between the bearing plate 95 and the flanges of the yoke end of the bar 92. Since the spring passes beyond center when the manual operating arm 23 is in the position shown in Figure 1, where the handle 60 is against the shoulder 82 and since the spring also passes beyond center when the handle 60 is moved against the shoulder 83 and the interposer 50 is thus moved from its position between the contacts, the action of the spring is to yieldingly maintain the manual operating arm 23 in whatever position it may be set, whether in open circuit position (against the shoulder 82) or in closed circuit position (against the shoulder 83).

In order that (upon removal of the barrier 50 from the position shown in Figure 1 of the rotation thereof about the pivot 72 in a counterclockwise direction with respect to Figure 1 so that no barrier is present between the contacts 40 and 42), the movable contact should be forced into closed current conducting contact with the stationary contact, a lever spring 100 is provided which tends to drive the movable contact surface 41 down upon the stationary contact surface 42.

The lever spring 100 is mounted upon a surface 101 of the housing and secured thereto by a washer 102 and one of the rivets 22a which serves to secure the cover plate to the housing. In order to ensure that the leaf spring will be accurately positioned to exert proper contact pressure upon the movable contact, a lug 103 extends from the leaf spring and registers with a recess 104 of the housing which registry serves

to prevent undue rotation of the leaf spring around the screw 22a.

The leaf spring 100 preferably is formed of any suitable elastic metal preferably of spring steel and is so arranged and bent as to exert pressure upon the contact-carrying arm 38 in such direction as to bias the contact block 40 and the movable contact surface 41 thereof into engagement with the stationary contact surface 42, the end 110 of the leaf spring 100 is sheared in such manner as to provide a pressure transmitting surface 111 thereon which presses down upon the contact bar and to provide guide flanges 112 and 113, the edges of which engage the sides of the contact-carrying bar 38, and prevent the escape of the contact-carrying bar from the leaf spring and vice-versa.

In order to obviate any friction that might be induced by the movement of the barrier between the contacts, a wheel 120 made of suitable insulating material is loosely mounted upon a rivet 121 which is in turn mounted in the perforation 122 of the movable contact block 40.

The stationary contact surface 42 projects somewhat as will be seen in Figure 3, above the main portion of the stationary contact-carrying bar 43. In order to protect the Bakelite housing 20 from the effects of any momentary arcing that may occur during the instant of breaking of the contacts, an insulating plate of any suitable material 130 is placed upon the inner side of the housing and over the stationary contact supporting members.

The insulating plate 130 has an opening 131 which registers with the stationary contact surface 42 and an opening 132 which registers with the wheel 120.

A small plate 136 of insulating material is placed beneath the opening 132 to protect the housing 20 at 135 from any stray arcs that might momentarily exist. The existence of the opening 132 as will be seen in Figure 3 permits the contacts 40 and 42 to come into close abutting relation without any interference from the wheel 120.

When the interposer 50 slides between the contacts, it will first strike the wheel 120, thus raising the contact bar sufficiently to permit the interposer to pass between the contacts. The removal of the interposer from between the contacts is not inhibited by the surfaces of the contacts but the interposer slides beneath the wheel and when withdrawn from beneath the wheel 120 the contacts may be engaged as seen in Figure 3.

An automatically operable interposer 150 is provided in order automatically to separate the contacts either in response to a sudden large drop in resistance or in response to an overload of lesser intensity but continuing to such an extent as to cause overheating.

The automatic interposer also comprises a central pivoting portion 151 which is mountable upon the spindle 12 and a latch engaging arm 152, and is arranged for mounting upon the spindle 12 in exactly the same manner as is the interposer 50, it, however, engaging the enlarged portion 154 of the spindle.

Thus the automatically interposable member 150 is first placed upon the side portion 154 of the spindle and then the manually operated interposer is placed thereon. The automatic interposer 150 has the same type of knife edge bearing as the interposer 50 in order to limit the rotation thereof.

A compression spring 170 controls the move-

ment of the automatic interposer 150 and is mounted on a lead 171 which has a yoke which bears against a notch of the automatic interposer 150 in the same manner as has previously been described for the manual interposer 50 and the opposite end 174 is arranged to slide in the perforation 175 of the plate 85 in the same manner as is the link of the spring 90.

The compression spring 170 is so arranged that it is always exerting a force tending to move the automatic interposer 150 into position between the contacts.

The interposer 150 is restrained from counter-clockwise movement in response to the action of compression spring 170 by the latch engaging arm 152 thereof. The latch engaging arm 152 carries secured thereto by rivets or any other suitable fastening means, a steel bearing plate 180 which engages the latch 181 of the trigger 182. Upon movement of the trigger 182 in such a direction as to release the engagement between the metal bearing 180 and the latch 181 there is no further restraint upon the rotation of the barrier 150 and since the action of the compression spring 170 is such as to immediately initiate counterclockwise movement thereof with respect to Figure 1, then immediately upon such disengagement, the compression spring 170 will force the interposer 150 into position where it extends between the movable and stationary contacts.

The open circuit position of the barrier 150 is definitely fixed by the abutment thereof against the edge of the handle shutter 50 which thus halts continued rotation of the interposer 150 in response to the action of the spring 170.

By proper arrangement and spacing of the shutters (that is the closed circuit non-interposing position of the shutter 50 and the open circuit interposing position of shutter 150), it is possible to ensure that in the tripped position of the circuit breaker, the interposer 150 will be positioned directly between the movable and stationary contacts.

The abutment of the edges of the shutter in the tripped position forms a complete continuous seal between the contacts cutting off any possible effective arc path.

When by the operation of the manual operating lever 23, the barrier 50 is moved to closed circuit position, that is, to a position where it no longer extends between the movable contact and the stationary contact, no impediment of any kind exists to the automatic interposition of the interposer 150 between these contacts in response to a release of the latch engaging portion thereof 150 by the trigger 182.

Normally when no fault conditions exists upon a line, the trigger 182 is so arranged that the latch portion 181 thereof engages the bearing plate 180 of the interposer 150. For the purpose of retaining the interposer in the desired non-interposing position, the trigger 182 is spring biased by means of springs 200 (Figures 1 and 2) into latching position.

The trigger is mounted upon a spindle 210 preferably integrally formed from and secured to the wall of the housing and preferably having a notch therein within which a pointed projection of the latch may register to obtain a bearing of the type previously described in connection with interposers.

Any fault condition existing upon the line must be manifested in some mechanical way which may be utilized to cause a rotation of the trigger in such a direction as to release the latch engag-

ing portion 152 of the interposer from the latch 181 of the trigger. Accordingly, arms 220 and 221 are provided on the trigger to cooperate with elements which respond mechanically to variations in the amount of current.

Trigger release arm 220 is so arranged as to cooperate with the member 245 of the solenoid assembly 230. As has been above noted, the solenoid is in the current path through the movable and stationary contacts. Thus, with respect to Figure 1, the current enters at the connecting lug or terminal 45, passes through the contact blocks and the member 39 and 38 into the coils 37 of the solenoid and thence through the wire braid 35, the thermal element 34 and the lug 33 and bar 32 into the opposite terminal 30.

The solenoid coil 37 is composed of several turns of conducting material which, in the preferred embodiment of the present invention, is square copper of substantial cross-section. The large cross-sectional area minimizes the resistance which is injected into the circuit and also increases the actual physical strength of the coil, thus making it possible to use an integral extension 38-39 of the solenoid coil itself as the lead-in and physical support for the movable contact block.

It will be noted that the contact engaging spring 100 forces the contact member 40 toward the molded wall of the housing. The point of engagement of this spring with the bar 39 is between the contact and the coil. The spring thus produces reactions at each end of the bar 38-39; one, producing contact engaging pressure when the interposers are retracted; the other maintaining the solenoid assembly in its socket.

To obviate the necessity for insulation on the solenoid, the coil preferably is wound with a reasonably large air space between the turns. The solenoid coil 37 is mounted on an insulating sleeve 231 which prevents any current leakage between the successive turns of the coil and at the same time serves to insulate the coil from other members of the mechanism.

The insulating sleeve 231 may be secured within the housing in any suitable manner. Thus one end thereof may at 232 be supported in a depression of the bottom wall of the housing and the opposite end thereof may be supported in a U-shaped member 233 preferably integrally molded from a wall of the housing.

A suitable steel core may be mounted within the sleeve 231 and may have a flange which registers with the depression in the bottom wall of the housing. Any suitable spring may be utilized within the sleeve to maintain the solenoid armature 240 in raised although slidable position within the spring; the said spring being calibrated to permit the drawing of the armature 240 within the coils in response only to an overload sufficiently excessive to cause damage and should resist the tendency of the armature to move within the coils upon the occurrence of overloads which are not greatly excessive but are merely sufficient to cause the generation of heat.

A rectangular trigger arm engaging member 245 is secured either by welding or by any other suitable means to the top of the armature. Preferably, the trigger arm engaging member 245 is squared-off and preferably the interior wall 246 is close to the plate 245 of the armature.

While the squaring-off of the plate 245 does not interfere with the rise or fall of the armature, it prevents undue rotation of the armature to ensure that the trigger arm engaging portion

thereof will always extend in such a direction as to engage the trigger and to ensure that it will not rotate out of engagement with the trigger. Means for preventing eddy currents may be provided in any suitable manner.

When an overload occurs for any reason causing an excessive current to pass through the coil 37 of the solenoid, then the armature 240 is attracted into the coil of the solenoid, the plate 245 engages the trigger arm 220, presses the arm downwardly, causes a rotation of the trigger about the spindle 210 in a direction opposite to that in which the trigger was originally biased by the trigger spring 200, causes a movement of the latch portion 181 thereof out of engagement with the bearing 180 of the latch engaging arm 152 of the interposer 150 and thus removes any restraint upon the rotation of the interposer 150, thereby permitting the compression spring 170 to drive the interposer from closed circuit position to a position where the interposer 150 extends between the movable and stationary contacts.

Thus whenever the manual interposer 50 is moved counterclockwise with respect to Figure 1 from position between the contacts to the closed circuit position, then a free path is provided for the movement of the automatic interposer 150 to interposing position should an overload occur.

The automatic interposer 150 in its movement into position between the contacts obviously engages the wheel 120 in order to raise the movable contact bar in the manner previously described in connection with the manual interposer. The manual interposer 50 is off-set out of the principal plane of the main portion of the manual operating lever 23 so that it will be coplanar with the automatically operated interposer 150 to provide a means for resetting the interposer 150 by rotation of the finger grasping portion 160 of the manual operating arm 23.

When the interposer 150 moves between the contacts, since the circuit is then opened, any restraining force preventing resetting is removed. Upon rotation in a clockwise direction of the member 60 in the manual operating arm 23, the automatic interposer 150 is reset in closed circuit position and subsequently upon counterclockwise movement of the manual interposer 50, the contacts are permitted to meet as shown in Figure 3.

If, during such opening movement of the interposer 50, over current conditions still exist on the line, then the tripping action may again occur. It is thus absolutely impossible to hold the circuit closed when overcurrent conditions exist on the line and to this extent at least the present invention is a trip free circuit breaker.

It may be necessary or desirable to effect a similar tripping operation of the interposer 150 when an overload which is not greatly excessive but is nevertheless continuous occurs.

In order to accomplish this purpose, I provide a thermal bi-metallic element 34 which is responsive to heating effects which may occur in this circuit. The thermal bi-metallic element 34 is so arranged that the lower end thereof will be rotated clockwise under the influence of heat. The current path from the connecting lug 45 through the contacts and to the connecting lug 30 is through the thermal element 34. Thus the current is led from connecting lug 45 through the bar 44 to the contact surfaces 42 and 41, the contact supporting arm 39 and 38, the solenoid coil 37, the wire braid 35 to the thermal element; from the thermal element, the current flows into

the thermal element supporting arm 33, thence through the bar 32 to the opposite connecting terminal 30.

Any overload conditions on the line which may result in the passage of sufficient current to generate heat in the circuit but which may not be of sufficient intensity to energize the solenoid 230 may nevertheless be sufficient to cause a bending of the thermal element 34. The thermal element 34 preferably is so calibrated that it will bend into engagement with the arm 221 of the trigger under predetermined excessive load conditions which are not greatly in excess of the desired current condition but which nevertheless result in the generation of excessive heat.

Upon bending of the thermal element 34 in response to such heating conditions in the circuit, the end thereof will be swung over into mechanical contact with the trigger arm 221 and will cause a rotation of the trigger 182 about the spindle 210, such rotation releasing the latch portion 181 thereof from the metallic bearing 180 of the latch engaging arm 152 of the automatically interposable interposer 150.

This permits a tripping operation to occur and permits the compression spring 170 to force the automatically operated interposer 150 into the open circuit position.

The automatically operated interposer may then be reset in the manner above described by the operation of the manual operating lever 23, but the trigger 182 will not be rotated to latching position by its spring 200 until the heating conditions which resulted in a curling of the thermal element 34 have been removed.

The circuit breaker may be calibrated for various types of overload conditions by any suitable adjustment of the solenoid or its armature or by adjusting the screw 270 of the thermal element. Since the finger grasping portion 60 may remain in the apparent closed circuit position against the shoulder 83 even though the automatic interposer 150 has been moved between the contacts, a visual indicator 300 may be provided carrying a flag 301 and having an opening 302 which permits it to be mounted on a spindle 72. A spring 308 tends normally to rotate the indicator 300 so that the flag 301 may be moved into the slot. A finger 305 however projects beneath the arm 152 of the automatic interposer and prevents the spring 308 from driving the flag upwardly into the slot.

Upon the raising of the arm by release of the latch plate 180, 180, the spring 308 may rotate the indicator 300 and drive the flag 301 into the slot thus giving a clear indication of the fact that the automatic interposer has been tripped, even though the finger grasping portion 60 should remain in apparent closed circuit position.

In order to prevent any possibility during the opening of the contacts of any arcing over between the movable contact block 40 and the bar 44, insulating barriers 320 and 321 are provided mounted in notch 322 of the ledge or boss 323 in the bottom wall of the housing and in notches 324 and 325 of an end wall of the housing, the said notches being integral with the housing.

In order further to protect the members against arcing, an upper shield 340 is provided (see Figure 2) having openings therein to permit the engagement of the contacts and the passage of the wheel therethrough. This protective shield may be formed or stamped to shape, the shape being, of course, determined by the contour of the housing and obviously this shield 340 is spaced from the

bottom shield 138 by a distance sufficient to permit the free passage of the insulating interposers between them.

From the foregoing description it will be seen that each of the members of the circuit breaker is supported within the housing in such a manner that they may readily be assembled in connection therewith. The housing itself is so formed and constructed as to provide supporting elements of various types, most of which having hereinbefore been described. Thus, for instance, the bar 32 which is an extension of the connecting lug 30 is securely mounted within the housing assembly by the screw 360 which passes through a lug 361 of the bar 32 and into an integrally molded rectangular support 363 of the housing. The bar 32 is also securely positioned within the housing by being mounted between the rectangular abutment 363 and the angular portion 364 of the housing.

Each of the interposers and the manual operating lever rotates about a single spindle which is integrally molded from or secured to one wall of the housing.

The member 44 which carries the lug 45 is also securely mounted within the housing, as is seen in Figure 1, by being mounted in a recess or channel 366 thereof. The various portions of the housing cooperate with other elements to provide stops for certain of the movements and to provide mountings and securement in the manner hereinbefore described. When the cover plate is secured in place by the rivets 22, then each of the members is securely fixed in its operative position. Thus, the final securement of all of the members is obtained after most of the members have merely been slipped into place by the attachment of the cover element 21 and the passing of the rivets 22 through the elements and the housing.

The lead connecting lug 30 is protected by the curved extension 390 of the housing and may be enclosed between the cover plate and this extension. The lead 45 may, if desired, extend from the opposite side or it may, where necessary, be protected in a similar manner.

The present circuit breaker is comprised of a magnetic trip and a thermal time delay element and may be incorporated in the usual form of power and light panel to handle branch circuits. The members as has been noted, are readily mounted in any suitable support upon the panel and require no more space than a fused switch, and, taking into consideration the expense of replacement of fuses and the expense of operation of the fused switch, they are better than an adequate substitute therefor.

They are designed to be mounted in a panel with a number of units side by side with the line terminal of each circuit breaker screwed directly to the common bus, this screw also serving to hold one end of the unit mechanically, the opposite end of the circuit breaker being mechanically supported in any suitable manner. In this manner, therefore, any individual units may be removed and replaced without disturbing adjoining units.

As has been above noted, the circuit breaker of the present invention is trip free in that it will open even though the handle is held in closed position and the switch cannot be held against overload or short circuit. The only way in which the circuit breaker may be reset after the interposer has been tripped is by moving the manually interposable interposer between contacts and thus maintaining the contacts in open cir-

cuit position. Should the circuit protected by the circuit breaker still be under overload conditions, then permitting the manually interposable interposer to be moved away from between the contacts will again cause the actuation of the thermal and/or solenoid elements to cause the automatically interposable interposer to move between the contacts and thus maintain the separation therebetween.

10 In the foregoing description while all of the operated elements have been set forth, it is particularly to be noted that each of these elements is mounted upon or supported by integral portions of the housing itself. Thus, the interposer 5 is mounted upon a spindle which is integral with or integrated with the housing. The latch is likewise mounted upon a spindle which is either integral with or integrated with the housing. The solenoid coil is mounted upon bearings which are integral with the housing and held within those bearings by a spring. The stationary contact is part of a lead-in bar which is mounted in recesses and channels within the housing.

15 The opposite terminal 30 and the connecting bar 32 is positioned by integral formations of the housing and secured to the housing. The spring which biases the movable contact and the various plates for preventing arcing over and for other purposes are each mounted in integrally formed portions of the housing.

20 All of the members, as has been specifically pointed out, may be placed within the housing by successive steps from one side of the housing and then the securement of the cover plate 21a 25 secures all of these members in place.

25 In the foregoing description cooperating elements have been set forth and the interrelation therebetween and especially the interrelation thereof with the housing have been specifically 30 described.

35 My specific invention is directed to the formation of the housing so that it will cooperate with each of the parts of the circuit breaker and support and position each of such parts.

40 Various modifications and changes in the different parts will now be obvious to those skilled in the art. Accordingly, it is desired to be bound not by the specific disclosures herein but only by the appended claims.

45 This application is filed simultaneously with the application of Frank J. Pokorny, Serial No. 331,984 for Circuit breaker, the application of Herbert C. Graves, Jr., Serial No. 331,982 for Circuit breaker, and the application of Otto Jensen, Serial No. 331,967 for Circuit breaker. In this application, I have claimed those inventions and portions of the structure devised by me.

50 I claim:

55 1. A panelboard circuit breaker comprising 60 switch members including separable contact means and manual and automatic current responsive means for controlling said contact means, a housing therefor adapted to be mounted upon a plane support in contiguous side by side 65 relation with other such housings, said housing comprising a box-like structure of rectangular shape having an open side, depressions in said housing communicating with the open side thereof, and cooperating with and positioning said 70 switch members, a rectangular opening in one edge of said housing and a manually operable member extending therethrough and adapted by pivotal movement to actuate said separable contact means to open and closed circuit positions, 75 a slot in one end of said housing, a first rigid

conducting terminal member extending therethrough, a perforation in said terminal on the outside of said housing for cooperation with screw means to connect said circuit breaker to an external circuit, the end of said terminal member inside of said housing being electrically associated with said separable contact means; a second conducting terminal member having one end electrically associated with said separable contact means and extending through a positioning slot in the end wall of said housing opposite to that traversed by said first terminal and means on the outside of said housing for connecting said second terminal to an external circuit, said housing having a plurality of channels lying in planes at substantial angles to each other for positioning each terminal the walls of the channels being substantially contiguous over their entire extent with surfaces of said terminals, a cover for the open side of said housing for maintaining said switch members therein and securing means for said cover.

2. A panelboard circuit breaker comprising switch members including separable contact means and manual and automatic current responsive means for controlling said contact means, a housing therefor adapted to be mounted upon a plane support in contiguous side by side relation with other such housings, said housing comprising a box-like structure of rectangular shape having an open side, depressions in said housing communicating with the open side thereof, and cooperating with and positioning said switch members, a rectangular opening in one edge of said housing and a manually operable member extending therethrough and adapted by pivotal movement to actuate said separable contact means to open and closed circuit positions, a slot in one end of said housing, a first rigid conducting terminal member extending therethrough, a perforation in said terminal on the outside of said housing for cooperation with screw means to connect said circuit breaker to an external circuit, the end of said terminal member inside of said housing being electrically associated with said separable contact means; a second conducting terminal member having one end electrically associated with said separable contact means and extending through a positioning slot in the end wall of said housing opposite to that traversed by said first terminal and means on the outside of said housing for connecting said second terminal to an external circuit, said housing having a plurality of channels lying in planes at substantial angles to each other for positioning each terminal the walls of the channels being substantially contiguous over their entire extent with surfaces of said terminals, each terminal comprising a flat strip of metal bent to cooperate with the sides of the channels for positioning the same therein, a cover for the open side of said housing for maintaining said switch members therein and securing means for said cover.

3. A panelboard circuit breaker comprising switch members including separable contact means and manual and automatic current responsive means for controlling said contact means, a housing therefor adapted to be mounted upon a plane support in contiguous side by side relation with other such housings, said housing comprising a box-like structure of rectangular shape having an open side, depressions in said housing communicating with the open side thereof, and cooperating with and positioning

75 said switch members, a rectangular opening in one edge of said housing and a manually operable member extending therethrough and adapted by pivotal movement to actuate said separable contact means to open and closed circuit positions, a slot in one end of said housing, a first rigid conducting terminal member extending therethrough, a perforation in said terminal on the outside of said housing for cooperation with 10 screw means to connect said circuit breaker to an external circuit, the end of said terminal member inside of said housing being electrically associated with said separable contact means; a second conducting terminal member having one end electrically associated with said separable contact means and extending through a positioning slot in the end wall of said housing opposite to that traversed by said first terminal and means 15 on the outside of said housing for connecting said second terminal to an external circuit, said housing having a plurality of channels lying in planes at substantial angles to each other for positioning each terminal the wall of the channels being substantially contiguous over their entire extent with surfaces of said terminals, 20 each terminal comprising a flat strip of metal bent to cooperate with the sides of the channels for positioning the same therein, a cover for the open side of the housing, said first terminal being positioned solely by the walls of the channels and the cover; said cover maintaining the switch members within the housing and securing means for the cover.

4. A panelboard circuit breaker comprising 25 switch members including separable contact means and manual and automatic current responsive means for controlling said contact means, a housing therefor adapted to be mounted upon a plane support in contiguous side by side relation with other such housings, said housing comprising a box-like structure of rectangular shape having an open side, depressions in said housing communicating with the open side thereof, and cooperating with and positioning 30 said switch members, a rectangular opening in one edge of said housing and a manually operable member extending therethrough and adapted by pivotal movement to actuate said separable contact means to open and closed circuit 35 positions, a slot in one end of said housing, a first rigid conducting terminal member extending therethrough, a perforation in said first terminal on the outside of said housing for cooperation with screw means to connect said circuit breaker to an external circuit, the end of said first terminal member inside of said housing being electrically associated with said separable contact means; a second conducting terminal 40 having one end electrically associated with said separable contact means and positioned by a positioning slot in the end wall of said housing opposite to that traversed by said first terminal, said housing having a plurality of channels lying in planes at substantial angles to each other for 45 positioning said first terminal; the walls of the channels being substantially contiguous over their entire extent with the surface of said first terminal, a cover for the open side of said housing for maintaining said switch members therein and securing means for said cover.

5. A panelboard circuit breaker comprising 55 switch members including separable contact means and manual and automatic current responsive means for controlling said contact means, a housing therefor adapted to be mount-

ed upon a plane support in contiguous side by side relation with other such housings, said housing comprising a box-like structure of rectangular shape having an open side, depressions in said housing communicating with the open side thereof, and cooperating with and positioning said switch members, a rectangular opening in one edge of said housing and a manually operable member extending therethrough and adapted by pivotal movement to actuate said separable contact means to open and closed circuit positions, a slot in one end of said housing, a first rigid conducting terminal member extending therethrough, a perforation in said first terminal on the outside of said housing for cooperation with screw means to connect said circuit breaker to an external circuit, the end of said first ter-

5 minal member inside of said housing being electrically associated with said separable contact means; a second conducting terminal having one end electrically associated with said separable contact means and extending beyond the end wall of said housing opposite to that traversed by said first terminal; said housing having a plurality of channels lying in planes at substantial angles to each other for positioning said first terminal; the walls of the channels being substantially contiguous over their entire extent with the surface of said first terminal, a cover for the open side of said housing for maintaining said switch members therein and securing means 10 for said cover.

15 WILLIAM M. SCOTT, JR.
